UNITED STATES PATENT OFFICE

ADOLPH M. ZUCKERMAN, OF NEW YORK, N. Y., ASSIGNOR TO R. HOE & CO., INC., OF NEW YORK, N. Y., A CORPORATION OF NEW YORK

FOLDER FOR PRINTING MACHINES

Application filed September 9, 1929. Serial No. 391,200.

This invention relates to folders for printing machines of the class used for printing magazines and similar products, and is adapted to perforate these products, so they 5 may conveniently be bound in a loose leaf binder.

It is the especial object of the invention to provide a folder having mechanism incorporated therein, that will receive a cut 10 product, convey it to a perforating mechanism, register it, hold it in register, perforate it, and then forward it to a delivery point.

It is also an object of the invention to provide a folder having a perforating mechanism incorporated therein, which will be simple, durable and inexpensive in construction, 15 as well as convenient, practical, serviceable and efficient in its use.

With the foregoing and other objects in view, which will appear as the description proceeds, the invention resides in the combination and arrangement of parts, and in the details of construction hereinafter described and claimed, it being understood that 20 various changes in the precise embodiment of the invention herein disclosed may be made within the scope of what is claimed without departing from the spirit of the invention.

30 In the accompanying drawings:

Figure 1 is a side view of a portion of a folder showing the invention in the preferred form;

Figure 2 is a vertical sectional view of a 35 portion of the folder as it appears on the line 2—2 of Figure 1, as viewed in the direction of the arrow;

Figure 3 is a fragmentary sectional view of part of the perforating mechanism as seen on the line 3—3 of Figure 1 and in the direction of the arrow;

Figure 4 is a sectional view of the holder for one of the punches as it appears on the line 4—4 of Figure 3 and in the direction of the arrow;

Figure 5 is a fragmentary view of a part of the perforating mechanism as viewed in the direction of arrow 5 of Figure 4;

50 Figure 6 is a view of one of the die holders

as seen in the direction of arrow 6 of Figure 5; and

Figure 7 is a view of the die holder shown in Figure 6 as seen in the direction of arrow 7 of Figure 6.

Referring to the drawings, 11 and 11' indicate side frames of a folder for a web printing machine, that carry bearings for the various cylinders and rollers shown.

In the embodiment of the invention here- 60 in disclosed, a portion of a folding cylinder is shown at 12. Grippers 13, and a tucking blade 14, are carried by the cylinder 12, the blade 14, being arranged to cooperate with jaws 15, on the transfer cylinder 16.

65 Stripper fingers 17, are arranged to run in suitable grooves in the cylinder 16, and act to remove the folded product therefrom and direct it to the guides 18, of the perforating mechanism.

Front stops 19, are secured to arms 21, which are fastened to a shaft 22, rotatably supported in bearings in the frames 11 and 11'. An arm 23, is also secured to the shaft 22, and carries a roller 24, which engages a 75 grooved face cam 25, secured to the shaft 26, which has bearings in the frame 11 and 11', and in the bracket 27, which is secured to the frame 11'.

A back jogger 28, is secured to an arm 29, 80 which is fastened to a shaft 31, rotatably supported in bearings in the frames 11 and 11'. An arm 32, is also secured to the shaft 31, and carries a roller 30, which engages another grooved face cam 33, secured to the shaft 26. 85 Presser and stripper bars, one of which is shown at 34, are secured to arms 35, which are fastened to the shaft 36, which is rotatably supported in bearings in frames 11 and 11'. The arms 37 and 38, are also secured to the shaft 36. Arm 37 is connected by a pivot pin to the rod 39, which carries a roller 41, that engages an open cam 42, secured to the shaft 26. The rod 39 is forked at its lower end as indicated at 43, to engage opposite sides of the shaft 26, which thereby holds it in proper alignment. The arm 38 is connected by a pivot pin to the rod 44, which is fitted to slide in the poppet head 45, secured to the frame 11. A spring 46, is placed between 100

the poppet head 45 and a washer 47, on the rod 44, and acts to press the presser and stripper bar 34, downward.

Punches 48, which engage with stationary dies 49, are secured to the sliding heads 51, that are fitted to slide in ways 52, secured to the brace 53. Means for adjusting the ways to compensate for wear are provided by the screws 54.

The heads 51, are formed with lugs 55, to which links 56, are pivotally connected. These links are similarly connected to arms 57, secured to a shaft 58, rotatably supported in bearings in the frames 11 and 11'. Another arm 59, is also secured to the shaft 58, and is pivotally connected to the rod 61, which is forked at 62, to engage opposite sides of the shaft 26, and carries a roller 63, which engages a grooved face cam 64, secured to the shaft 26.

Lower forwarding tapes or belts 65, pass around tightener pulleys 66, and fixed pulleys 67, and are driven by the cylinder 68, which is secured to the shaft 69, to which the gear 71 is keyed. Upper forwarding tapes 72 pass around pulleys 73, which are loose on the shaft 58, under tightener pulley 74, around pulleys 75, which are spring pressed into engagement with the cylinder 16, over the cylinder 68, and around pulleys 76, secured to the shaft 77, to which the gear 78 is keyed.

The gear 78, meshes with the gear 71, which meshes with gear 79, which is loose on the shaft 26. Gear 81 is secured to cylinder 16, and meshes with gear 79, and also with gear 82, secured to cylinder 12. An arm 83, secured to the shaft of the cylinder 16, carries a crank pin 84, to which a rod 85, is connected. The other end of this rod is connected at 86, to an arm 87, secured to the shaft 88, which is rotatably supported in the frames 11 and 11'. The arm 89, is also secured to the shaft 88, and pivotally connected at 91, with the link 92, which is connected at 93, with the slider 94, which is fitted to the slide 95, and carries packer fingers 96, which thus are given a reciprocating motion, into and out of the packer box 97.

A clutch member 98, slides on a feather on the shaft 26, and engages with a mating clutch member formed on the gear 79. This provides means for connecting and disconnecting the gear 79 and the shaft 26.

In the operation of the mechanism shown, the printed and cut sheets are carried on the folding cylinder 12, and transferred to the cylinder 16, being then folded to form a signature. From the cylinder 16, they are removed by stripper fingers 17, and are then engaged by the tapes 65 and 72, between which they are forwarded to the punching mechanism. Their motion is arrested by the front stops 19, and the back jogger stop 28, then rises and properly positions them. The sheets are thus arranged in proper register for

punching. The presser and stripper bars 34, then bear down and hold them securely, while the punch is operating. As the punch rises, the sheets are stripped therefrom, the stops descend below the guides 18, the bars 34 are raised, and the perforated product is carried forward to the discharge point or delivery indicated at 99. In the embodiment of the invention shown, the product is then dropped on edge, in the packer box 97, where the fingers 96, push each signature and those ahead of it forward after it is delivered, in order to make space for the following signature. If desired, side joggers may be added to align the sheets sideways before they are perforated. These can be operated by a well known mechanism, and will be found advantageous in handling some kinds of products.

It will be understood that the mechanism may be operated to punch the product before delivery as described, or that by disconnecting the clutch 98, the stop operating mechanism, the presser device and the punching mechanism may be silenced and the product will then be delivered without being punched.

It will also be understood that the punching mechanism herein disclosed for punching previously folded products, can be used to punch sheets forwarded directly from cutting cylinders and unfold, and if desired, the conveying mechanism may be arranged to deliver them to a mechanism whereby they may be folded after punching.

It will furthermore be understood that the term "folder" is herein used to designate the portion of the machine that cuts the previously printed web into sheets, and perhaps collects several such sheets that may be folded before delivery, thus forming a combined product, or the sheets may be delivered flat without being folded.

What I claim is:

1. In combination with a printing machine folder, a perforating mechanism including a reciprocating punch, means for conveying a previously printed and cut product to the perforating mechanism and to a delivery point, means for registering the product for perforating, and means for compressing the product adjacent to the point at which it is perforated and holding it compressed while it is being perforated and while the punch is being withdrawn.

2. In combination with a printing machine folder, a perforating mechanism including a reciprocating punch, means for conveying a previously printed and cut product to the perforating mechanism to a delivery point, means for registering the product for perforating, means for compressing the product adjacent to the point at which it is perforated and holding it compressed while perforating it while the punch is being withdrawn; said registering means and said compressing

means being driven in timed relation to the perforating means.

3. In combination with a printing machine folder, a perforating mechanism including a reciprocating punch, means for conveying a cut and folded product from the folder to and from the perforating mechanism, means for registering the product for perforating, and means for compressing the product adjacent to the point at which it is perforated and holding it compressed while it is being perforated and until the punch is withdrawn.

4. In combination with a printing machine folder, a perforating mechanism including a reciprocating punch, means for conveying a cut and folded product from the folder to and from the perforating mechanism, means for registering the product for perforating, means for compressing the product adjacent to the point at which it is perforated and holding it compressed while perforating it and until the punch is withdrawn; said registering means, said compressing means, and said perforating mechanism, being driven in timed relation to the folder.

5. In combination with a printing machine folder, a perforating mechanism including a reciprocating punch, means for conveying a previously cut product to and from the perforating mechanism, means for stopping and registering the product for perforating, means for compressing the product adjacent to the point at which it is perforated and holding it compressed while perforating it and until the punch is withdrawn.

6. In combination with a printing machine folder, a perforating mechanism including a reciprocating punch, means for conveying a previously cut product to and from the perforating mechanism, means for stopping and registering the product for perforating, means for compressing the product adjacent to the point at which it is perforated and holding it compressed while perforating it and until the punch is withdrawn; said registering means and said compressing means being driven in timed relation to the perforating means.

7. In combination with a printing machine folder, a folding mechanism, a perforating mechanism including a reciprocating punch, means for conveying a cut and folded product from the folding mechanism to the perforating mechanism and then to a delivery, means for registering the product for perforating it, and means for silencing the registering mechanism and the perforating mechanism, whereby the product may be delivered without being perforated.

8. In combination with a printing machine folder, a folding mechanism, a perforating mechanism including a reciprocating punch, means for conveying a cut and folded product from the folding mechanism to the perforating mechanism and then to a delivery,

means for stopping and registering the product for perforating it, means for compressing the product and holding it compressed while it is being perforated, and means for silencing the registering mechanism, the compressing mechanism and the perforating mechanism, whereby the product may be delivered without being perforated.

9. In combination with a printing machine folder, a perforating mechanism including a reciprocating punch, means for conveying a previously cut product to the perforating mechanism and to a delivery, stopping and jogging means to register the product for perforating, means for compressing the product adjacent to the point at which it is perforated and holding it compressed while perforating it and until the punch is withdrawn.

In testimony whereof, I affix my signature.

CERTIFICATE OF CORRECTION.

Patent No. 1,885,313.

November 1, 1932.

ADOLPH M. ZUCKERMAN.

It is hereby certified that error appears in the printed specification of the above numbered patent requiring correction as follows: Page 2, line 104, for the mispelled word "foldded" read "folded"; line 124, claim 2, after "mechanism" insert the word "and", and line 129, after "it" insert the word "and"; and that the said Letters Patent should be read with these corrections therein that the same may conform to the record of the case in the Patent Office.

Signed and sealed this 17th day of January, A. D. 1933.

(Seal)

**M. J. Moore,
Acting Commissioner of Patents.**
